LIGHT PROJECTING SYSTEM

Theodore Lindenberg and Theodore Linden-
berg, Jr., Columbus, Ohio

Application November 20, 1934, Serial No. 753,950

3 Claims. (Cl. 88—24)

This invention relates to improvements in light projecting systems and has particular reference to a novel method and means by which a beam of light emanating from a single source, may be intercepted and reflected to produce a plurality of spaced beams which may be directed in a controlled manner toward different points.

The invention is more specifically concerned with the projection of motion pictures in theater buildings employing dual auditoriums whereby through an improved system of light projection, pictures projected from a single machine may be directed, at will, upon the screens of such auditoriums, thereby avoiding the present necessity for providing projecting apparatus for each auditorium.

In the prior application of the applicant, Theodore Lindenberg, Serial No. 747,041 filed October 5, 1934, there has been disclosed a system of mirrors arranged to intercept a light beam issuing from a motion picture projecting machine whereby to divert the light beam and divide the same into two or more beams traveling in different directions. It is a particular object of the present invention to utilize the general features of the invention set forth in the aforesaid application but, in addition, to modify the formation and locations of the light reflecting mirrors to the end of enabling the light projected on the spaced screens of the auditoriums to be of uniform intensity over the full illuminated areas of said screens.

For a further understanding of the invention, reference is to be had to the following description and the accompanying drawings, wherein:

Fig. 1 is a horizontal sectional view taken through a theater building equipped with dual auditoriums and utilizing the light projecting system comprising the present invention;

Fig. 2 is a similar view on a larger scale disclosing the arrangement of the light reflecting mirrors comprising the present invention by which light from a single source is divided to produce a plurality of beams which are directed toward the screens of said auditoriums;

Fig. 3 is a perspective view of the plain and apertured mirrors utilized by the present invention;

Fig. 4 is a front elevation of the apertured mirror;

Fig. 5 is a similar view of the plain mirror;

Fig. 6 is a vertical sectional view taken through the apertured mirror on the line VI—VI of Fig. 4.

In Fig. 1, the outer walls of the theater building have been designated by the numeral 1, the

numeral 2 designates a central or divisional wall which divides the building into a plurality of auditoriums 3—3. In the front of each auditorium there is arranged a motion picture display screen or other equivalent surface 4 upon which motion pictures are adapted to be projected. In the rear of the building, there is formed the usual projection room 5 in which is received one or more standard motion picture projection machines 6. It will be understood that in motion picture theaters two projection machines are employed and which are used alternately for the purpose of producing a continuous display of motion picture reels. However, for the sake of clearness, but one of such machines has been disclosed.

The light projecting lens barrel of the projecting machine is designated by the numeral 7 and from which issues the customary strong beam of light which for a short distance in front of the projecting machine is substantially round or circular in cross section, the said beam of light being designated in Fig. 2 by the reference character *a*. Arranged in the path of projection of the light beam *a*, in the specific embodiment of the invention here under consideration, are apertured and plain mirrors 8 and 9 respectively. In this instance, the mirrors are spaced relatively approximately 90° apart and are arranged in the principal axis of the beam *a*. If desired, the mirrors may be removably mounted within a casing 10, supported in connection with the front wall of the projection room 5, the said casing being formed with an opening 11 through which the beam *a* passes.

In order to obtain uniform intensity of illumination over the full light receiving areas of the screen 4, we have found it necessary to utilize an unusual arrangement of silvered surfaces on the mirror 8. It will be noted that the apertured mirror is disposed at an angle of approximately 45° to the principal axis of the beam *a* and that this beam is substantially circular in cross sectional formation when projected on the surfaces of said mirror and therefore in order that the light beams *b* and *c* reflected from the surfaces of both the mirrors 8 and 9, in paths substantially 90° to the principal axis of the beam *a*, will be of uniform cross sectional intensity, and to avoid light and dark areas on the screens 4, we have constructed the mirror 8 to include a plurality of spaced diverging clear glass slots or apertures 12 which are spaced or separated by corresponding mirror strips 13, the said strips and apertures increasing in width or trans-

verse thickness from the left toward the right edge of the glass plate constituting the mirror body.

By this arrangement, light incident on the strips 13 will be reflected to produce the beam b while those rays of the beam a which are not intercepted by the mirrored strips 13 will pass through the apertures 12 and will be intercepted by the surface of the plain mirror 9 so as to reflect the same to produce the beam c which advances in a direction directly opposed to that of the beam b. Moreover, since the apertured mirror is arranged at a 45° angle to the axis of the beam a and since said latter beam is substantially circular in cross section, the said beam when contacting with the mirror 8 possesses a non-circular configuration of substantially the formation indicated by the dotted lines d in Fig. 4. The angular arrangement of the alternate apertures 12 and the strips 13 of the mirror 8 adapts said mirror to the cross sectional configuration of the light beam a as indicated at d so that light rays of uniform intensity will pass through the apertures 12 and will be reflected from the surfaces of the mirror 9 to comprise the beam c.

The beams b and c are projected toward mirrors 14 and 15 respectively arranged in the ends of the casing 10 at angles of substantially 45° with respect to the principal axes of the beams b and c, whereby light beams e and f will be reflected respectively from said mirrors 14 and 15 through registering openings 16, formed in the ends of the casing 10 and the front wall of the projection room, in order that said beams e and f may be directed upon the picture displaying screens 4 of the auditoriums 3. The mirrors 14 and 15 are somewhat larger than the mirrors 8 and 9 in order to compensate for the increase in cross sectional area of the beams b and c during travel of the latter from the mirrors 8 and 9 to the mirrors 14 and 15.

By virtue of the peculiar formation of the apertured mirror as herein disclosed, it will be seen that the present invention solves the problem of evenly and uniformly illuminating each of a plurality of spaced screens from a single source of light projection. In the aforesaid application, of which the present application constitutes a continuation-in-part, there has been disclosed a system of projecting light by which two or more screens may be simultaneously illuminated from a single source of light projection. However, by the present disclosure, a further and very important improvement is effected in obtaining uniform increments of illumination over the full light receiving areas of such screens.

What is claimed is:

1. In a motion picture projecting system, the combination with a pair of parallel adjoining auditoriums, apparatus for projecting a primary beam of light through a motion picture film, a screen intercepting said primary light beam and disposed in angular relationship to its principal axis, said screen comprising a plurality of spaced mirrored light-reflecting areas running transversely of the mirror in increasing width and intervening non-reflecting light-transmitting areas corresponding thereto, said mirrored areas producing a secondary light beam projected in a course substantially at right angles to that of the

primary light beam, an angularly disposed mirror for receiving the non-reflected light rays of the primary beam following passage of the latter through the non-reflecting light-transmitting areas of said screen, the angularity of said last-named mirror producing a tertiary light beam projecting substantially at right angles to the axis of the primary beam and in an opposed direction to that of the secondary beam, and angularly disposed mirrors intercepting the secondary and tertiary beams and reflecting the latter longitudinally through said auditoriums.

2. In a motion picture projecting system, the combination with a pair of parallel adjoining auditoriums, apparatus for projecting a primary beam of light through a motion picture film, a screen intercepting said primary light beam and disposed in angular relationship to its principal axis, said screen comprising a plurality of spaced mirrored light-reflecting areas running transversely of the mirror in increasing width and intervening non-reflecting light-transmitting areas corresponding thereto, said mirrored areas producing a secondary light beam projected in a course substantially at right angles to that of the primary light beam, an angularly disposed mirror for receiving the non-reflected light rays of the primary beam following passage of the latter through the non-reflecting light-transmitting areas of said screen, the angularity of said last-named mirror producing a tertiary light beam projecting substantially at right angles to the axis of the primary beam and in an opposed direction to that of the secondary beam, angularly disposed mirrors intercepting the secondary and tertiary beams and reflecting the latter longitudinally through said auditoriums, and screen means disposed at the forward ends of the auditoriums to intercept the light beams projected through the latter.

3. In a motion picture projecting system, apparatus for projecting a primary beam of light through a motion picture film, a screen intercepting said light beam and disposed in angular relationship thereto, said screen comprising a plurality of spaced mirrors of strip formation running transversely of the mirror in increasing width and intervening non-reflecting light-transmitting areas of corresponding formation, said strips converging toward one side of said screen, the mirrored areas of said screen producing a secondary light beam projected in a course substantially at right angles to that of the primary light beam, an angularly disposed mirror for receiving the non-reflected light rays of the primary beam following passage of the latter through the non-reflecting light-transmitting areas of said screen, the angularity of said mirror with relation to said primary beam being such as to produce a tertiary light beam projecting substantially at right angles to the axis of the primary beam and in an opposed direction to that of the secondary beam, and angularly disposed mirrors intercepting the secondary and tertiary beams and reflecting the same generally in directions parallel to that of the primary beam.

THEODORE LINDBERG.
